UNITED STATES PATENT OFFICE.

MAX JAHN, OF LEIPSIC-PLAGWITZ, GERMANY.

STOVE.

SPECIFICATION forming part of Letters Patent No. 599,709, dated March 1, 1898.

Application filed October 6, 1896. Serial No. 608,025. (No model.)

To all whom it may concern:

Be it known that I, MAX JAHN, a subject of the King of Saxony, residing at Leipsic-Plagwitz, Saxony, Germany, have made a new and useful Improvement in Stoves, of which the following is a full and clear specification.

My invention relates especially to improvements upon a patent granted to me, No. 522,015, dated June 26, 1894, wherein a central air-tube is encircled spirally by alternate heating and air conduits communicating, respectively, with the fire-chamber of the stove and the surrounding exterior air of the room to be heated; and the improvement consists particularly in the arrangement of the fire-chamber in connection with the central and spiral heating-conduits, in the air and draft regulating appliances connected therewith, and in means for discharging and circulating the highly-heated and the partially-consumed gases and thoroughly commingling them in their exit from and around the fire-chamber.

In the accompanying drawings, which illustrate my invention, Figure 1 is a central vertical section of my improved stove; Fig. 2, an enlarged vertical section of the cap and upper plates of the heating-drum; Fig. 3, a perspective view of the lowermost drum-section and part of the one above it, showing the spiral plates and interior connections; Fig. 4, a perspective view of the base cap or section for connecting the base and drum and also showing the feed-spout connected therewith, and Fig. 5 a perspective view of the feed-spout and the air and smoke separating plate to fit the base-cap.

The stove herein shown is built up of a series of ring-sections forming the heating-drum A and of other sections hereinafter described forming the base B, which comprises the body of the stove, a central section of the base providing a fire-chamber C, which is of novel construction, and a grate and ash-pan section D, forming the bottom ring, which rests upon the foot-ring E and may be set or connected therewith in any well-known or preferred manner.

The heating-drum A has a central air-flue F, the outer surface of which has a double series of ledges f f, and the inner surface of the several sections of said heating-drum have corresponding ledges a a, which are adapted,

when fitted together, to provide double parallel approximately-disposed tracks, upon which may be securely supported curved or helicoidal plates or metal sheets g and h to spirally encircle the said central air-flue F and provide two spiral passages of unequal area within the heating-drum. The space between said hot-air passages being divided by vertical partitions h', as shown in Fig. 3, one of the aforesaid passages forms the spiral combustion-conduit G, connected to the base and fire-chamber, and the other forms the spiral air-heating conduit H, having inlet-apertures H' to receive and similar outlet-apertures H" to discharge in horizontal planes the exterior air of the room after presenting it to the surfaces of the spiral heating-conduit H in a simple, rapid, and effective manner, the partitions h' within the air-passage serving to throw the air out of the drum after it has passed once around the central air-flue.

The central air-flue F is supported at its lower end upon the horizontal projection k of a feed-spout K, connected to the fire-chamber, and is supported at the top on an inner projection a' of the cap-section A', which latter fits upon the upper section of the heating-drum A and in turn supports the dome-section A² of said cap, which has a central opening flange a², upon which is fitted the stove-pipe A³, which carries off the smoke or final products of combustion. As shown clearly in Fig. 1 and by detail in Fig. 2, the dome-section A² has openings a³ on one side to receive the smoke from the combustion-conduit G, and openings a⁴ on the opposite side to receive the heated air both from the central air-flue F and also from the top extremity of the spiral heating-conduit H, the said dome-section being provided with apertures a⁵ therein, through which the heated air is conducted into the room.

The bottom plate g² of the smoke-conduit G rests upon the ledge k³ of the feed-spout K and passes around over a vertical partition b⁴ of a horizontal base-plate B⁴, which fits in the base-cap B⁵, the latter serving to connect the upper section of the base B with the lower section A⁵ of the heating-drum A, and also serving to support the horizontal projection k of the feed-spout. Suitable apertures b⁵

in the base-plate B⁴ admit smoke from the combustion-conduit of the base to the combustion-conduit of the drum, and also allows the smoke which passes through the small central channel k' of the feed-spout to enter the combustion-conduit G of the drum. A draft-regulating damper I, to fit the rectangular cross-section of the combustion-conduit G, is supported therein by a spindle g, by which 5 it is regulated.

The feed-spout K of the fire-chamber C extends angularly downward from the top b of the base-cap B⁵ and its junction with the foot of the heating-drum and is closed outwardly 15 by a door or cover G² and has a small central channel k' within the horizontal projection k, upon which the air-flue F is supported, the central channel k' serving to conduct the first products of combustion beneath the base of 20 said air-flue to the combustion-conduit G, a similar superimposed channel k² connecting the base of the air-heating conduit H with the air-flue F and also with an air-jacket C around the fire-chamber C, which extends to the base 25 thereof near the floor and carries off and heats the coldest air of the room from the bottom of the stove, as will hereinafter appear. The fire-chamber C being double-walled, the outer shell C' will not be heated to a white or equally 30 extreme heat, and the exterior shell of the base B will be heated to a degree still less extreme, a spiral hot-air channel B' between the base and fire-chamber, formed by the inner sheet-metal shell B², serving to effectively and 35 rapidly carry on the circulation and complete commingling of the gases and products of combustion, which is furthered materially by means of heat-discharge openings C² C² in the upper part of the fire-chamber and other 40 heat-discharging openings C³ C³ in the lower part of said fire-chamber. The walls of these openings are inclined upwardly to better carry off the combustion products and also to prevent the coal from falling out through them 45 from the fire-chamber.

Air is admitted to the fire-chamber C through the base B by means of a top draft-channel B³, covered by a screw-regulated register-plate b³, a middle draft-channel B⁴, covered by a hinged door having a supplemental register-plate b⁴ opening a short distance above the grate M, hereinafter described, and a bottom draft-channel B⁵, also having a register-plate b⁵ and opening in the ash-pan D 55 below the said grate.

The grate comprises the basket-section M² and a grate portion proper resting upon the flanges m⁶, the basket-section and grate proper having handles m⁴ and m⁵, by which they are 60 rotated and reciprocated, respectively, in any well-known or preferred manner.

Suitable air channels or openings b⁶ in the base admit air from the room into the hot-air channel B', and similar openings b⁷ at the 65 foot of the base admit cold air from near the floor by means of lateral channels b⁸ into the air-jacket surrounding the fire-chamber,

which communicates with the central air-flue of the heating-drum.

The operation of my improved stove is substantially as follows: The fire-chamber is first filled with coal through the feed-spout nearly or quite to the top thereof and settling within the basket-grate and upon the shaking-grate is provided with an extended grate-surface. The fire when first kindled receives air from the register below the grate, and the first smoke and products of combustion pass off directly and rapidly through the channel leading from the feed-spout at the top of the fire-chamber to the central air-flue to the chimney, the damper in the spiral combustion-conduit being properly regulated. After the coal has become thoroughly ignited the less perfectly consumed gases pass out through the upper discharge-openings C² C² of the fire-chamber, and the more highly heated gases and flame pass out from the fire-chamber through the openings C³ C³ thereof, and commingling, as shown by the arrows in Fig. 1, are conducted 70 together through the hot-air channel B' of the base, and thence joining the first products of combustion issuing from the channel of the feed-spout provide a final and practical combustion of said gases, the large grate area 75 adding greatly to the completeness of the combustion. The top draft-channel permits the air to be supplied and heated at the upper part of the fire-chamber, and the middle draft-channel, the opening of which is regulated 80 both by a register-plate and a door, admits air to the lower part or base of the fire-chamber, and when the full door of the latter is 85 opened will greatly accelerate the combustion and heat of the coals within the fire-pot.

All the conditions required for slow and perfect combustion of every pound of fuel are thus provided, and an extended grate-surface as well as an extended heating-surface, all under complete control, will in a most perfect manner cause a rapid circulation both of the cold air from the floor directly to the most highly heated channels to the warmer strata above, and also of the intermediate zone, which is conducted, as shown by the arrows 90 in horizontal lines, through the heating-drum and over the extended spiral surfaces of its air-heating conduit and discharged through numerous openings extending from the foot to the cap of the heating-drum. The air from the upper part of the room above the base portion of the stove passes into the spiral air-conduit H on one side, and after passing once around is intercepted by the vertical partitions h' and discharged at the opposite side 95 thereof. When the fire burns briskly, the central air-flue F becomes heated and either all or a portion of the air admitted to lower spiral air-conduit H is drawn into said flue 100 through the channel k² of the feed-spout, while any surplus air or air not drawn into the air-flue F will pass out into the room through the apertures in the drum leading 105 from the spiral air-conduit. A water-basin 110

N, fitted upon the cap-plate, will serve to hold water for evaporation, and a door O at the back and foot of the base provides access thereto for cleaning the stove.

5 I claim as my invention and desire to secure by Letters Patent—

1. In a stove, the combination with the base, of the fire-pot contained therein, and a spiral plate providing a hot-air channel between them, the said fire-pot being provided with discharge-openings respectively above and below said spiral plate to cause the commingling of the upper and lower products of combustion from the fire-chamber, and a heating-drum leading from the said hot-air channel, substantially as described.

2. In a stove, the base in combination with a double-walled fire-chamber contained therein, to provide an annular hot-air channel between them, the said fire-chamber being provided with heat and smoke discharge passages having upwardly and outwardly inclined walls to prevent the coal from falling through them from the fire-chamber and extending through the said annular hot-air chamber, substantially as described.

3. A stove comprising a base having a fire-chamber, a spiral air-jacket extending from the foot thereof to a discharge-opening at the top thereof, in combination with a heating-drum comprising a spiral combustion-conduit leading from the discharge-opening of the base to the top of the drum, a series of spiral air-heating chambers interposed between the convolutions of the combustion-conduit hav-

ing oppositely-disposed apertures in the outer walls of the said chambers to allow the air to pass transversely into and out of said chambers, and a stovepipe leading from the combustion-conduit, substantially as described.

4. In a stove the combination with a base and inner fire-chamber of a central air-tube, a spiral combustion-conduit leading from said chamber to the discharge-opening, and a feed-funnel leading through the walls of the base and fire-chamber having a horizontal pipe leading therefrom to the base of the spiral combustion-conduit, substantially as described.

5. The combination with a stove-base, of a central fire-chamber, a funnel-section having a horizontally-projecting pipe or conduit, a pipe-base thereon and a base-cap provided with a seat for supporting the drum formed integral, a spiral heating and a spiral combustion conduit comprising the drum supported upon said funnel-section with the base of the spiral combustion-conduit leading from the horizontal pipe of the funnel, and a central air-pipe supported upon the said funnel-section and supported within the drum, substantially as described.

In testimony whereof I have signed my name to this specification in the presence of two subscribing witnesses.

MAX JAHN.
